UNITED STATES PATENT OFFICE.

GEORGE TANDY SMITH, JR., OF PADUCAH, KENTUCKY.

LAYING COMPOSITION SHINGLES.

Application filed April 29, 1921. Serial No. 485,525.

To all whom it may concern:

Be it known that I, GEORGE TANDY SMITH, Jr., a citizen of the United States, residing at Paducah, in the county of McCracken and 5 State of Kentucky, have invented certain new and useful Improvements in Laying Composition Shingles; and I do hereby declare the following to be a full, clear, and exact description of the invention, such as 10 will enable others skilled in the art to which it appertains to make and use the same.

This invention relates to composition roofing, and more particularly to a new method of connecting and laying asphalt or other 15 composition shingles.

It is well known that strip or roll shingles which have machine cut joints or spacing, and consist practically of one piece of roofing, invariably buckle or become rough 20 in appearance, due to expansion or contraction or to the roof deck seasoning beneath them which individual shingles will not do, and the objects of my invention are to provide means for connecting individual asphalt or composition shingles and spacing 25 them in such manner as to avoid the trouble of spacing them by measurement when the roof is being laid, and to make the laying practically as economical as the laying of 30 the ordinary strip or roll shingles, and also to avoid the unsightly appearance of individual shingles when spaced by mere guess-work, and at the same time to retain all of 35 the advantages of individual shingles, which are much better in every way than the strip or roll shingles, and not to interfere in any 40 way with the present method of packing and shipping such shingles, whereby the time ordinarily required in laying individual shingles and consequently the cost of laying on the roof is greatly reduced.

The invention will first be hereinafter more particularly described, with reference to the accompanying drawings, which are 45 to be taken as a part of this specification, and then pointed out in the claims at the end of the description.

In said drawings,

Fig. 1 is a plan view illustrating two 50 series of flexibly connected asphalt or other composition shingles spaced apart and laid in accordance with my invention; and

Fig. 2 is an end view of one of said series 55 illustrating how the shingles may be folded to economize space in packing for transportation or storage.

Referring to said drawings, in which the same reference letters are used to denote corresponding parts in different views, the letters A, A, denote individual shingles or 60 sections of roofing material composed of asphalt or other composition and connected together so as to be handled as a unit by means of flexible strips B, B, of paper, cloth, or other suitable material secured to the undersides of the shingles by means of glue or 65 other adhesive substance, so as to render the strips invisible after the roof is laid, the individual shingles being spaced apart to the extent desired for roofing purposes. 70 Any desired number of shingles, within reason, may be connected together in the manner stated, to facilitate the laying and eliminate the necessity for spacing. As 75 shown, there are two connecting strips B, B, secured on the undersides of the series of shingles, and consisting preferably of tough paper, though other material and a greater or less number of strips may be used. The lower strip is adapted to serve as a "line" 80 for the next course of shingles to be laid, the bottoms or lower ends of the next course being laid directly over the lower edge of the lower connecting strip, which is placed the required distance from the lower ends 85 of the shingles, while the upper strip is secured near the upper ends of the series. The two strips are adapted to provide the exact spacing desired along the entire length of the sides of adjacent shingles. 90

Shingles connected as described may be laid in much less time and with much less trouble than individual shingles, with consequent saving in the cost of laying and spacing on the roof, as the connecting strips insure correct spacing between shingles and render it easy to place one layer or series upon another at the exact distance desired between the lower ends thereof and the subjacent course or their upper ends and the next succeeding course without requiring the use of any measuring instrument, and with absolute accuracy, which is not possible in laying individual shingles and spacing with the eyes, and at the same time all of the advantages of individual shingles are retained, and if any expansion or contraction occurs after the shingles are laid, the paper connections would naturally tear between shingles and would not interfere in any way with the shingles themselves. The connecting strips also permit the series of shingles 105 110

to be folded in compact form for storage or transportation.

Having thus described my invention, what I claim as new and desire to secure by Letters Patent is:

1. As a new article of manufacture, a series of individual shingle-like sections of roofing material connected together in slightly separated relation by strips of flexible material secured thereto by an adhesive substance, there being an upper and a lower strip extending longitudinally across the series, the lower strip being located at an intermediate point to adapt it to serve as a "line" for laying the next course of shingles with their lower ends directly over its lower edge.
2. A roof composed of individual shingles of a suitable composition, the individual shingles of each layer spaced apart and connected together by upper and lower flexible strips secured thereto by an adhesive substance, whereby the series may be handled as a unit and folded for storage or transportation, the lower connecting strip of each series being located at an intermediate point to adapt it to serve as a "line" for laying the next course of shingles with their lower ends over the lower edge of said intermediate connecting strip.
3. As a new article of manufacture, a se-

ries of individual sections of roofing material spaced apart and connected together by flexible strips secured thereto on the under sides thereof by an adhesive substance and extending across the series, one strip being arranged near one end and another at an intermediate point, the edges of adjacent sections being properly spaced for laying so that the lower connecting strip is adapted to serve as a "line" for laying the next succeeding course.

4. A series of individual sections of roofing material connected together in slightly separated relation and adapted to be handled as a unit and folded in compact form, the connections between the sections consisting of strips of paper secured on the under sides of the strips by an adhesive substance, one strip being located adjacent the upper ends of the series and another strip at an intermediate point, the intermediate strip being adapted to serve as a "line" for laying the next succeeding course or layer of connected sections.

In testimony whereof I affix my signature in the presence of two witnesses.

GEORGE TANDY SMITH, JR.
